MULTIPLE COATING APPARATUS

Stanley E. Wright, Fairport, N.Y., assignor to Eastman Kodak Company, Rochester, N.Y., a corporation of New Jersey

Filed Oct. 27, 1958, Ser. No. 769,881

4 Claims. (Cl. 118—407)

The present invention relates to hoppers to be used for applying simultaneously two or more layers of aqueous colloidal dispersions to a moving web of film base, paper, plastic sheeting, etc., said layers being applied in thicknesses varying one to another, and having different compositions resulting from the addition of varying amounts of solids, such as silver halide grains, matting agents, color couplers, gelatins, pigments, dyes, etc.

This invention relates to a multiple slide hopper for use in carrying out the method of multiple coating disclosed in U.S. Patent 2,761,791. Specifically, it is a modification of features disclosed in U.S. Patent 2,761,419 which relates to the basic multiple slide hopper.

The objects of this invention are: (1) to greatly extend the range of relative layer thickness which may be applied simultaneously to the surface of a web using a multiple slide hopper, and (2) to make possible the handling of fluid coating compositions containing higher proportions of granular solids, such as silver halide grains, matting agents, color couplers, pigments, etc., than is possible by the use of previously disclosed multiple coating apparatus, while at the same time maintaining uniformity of layer undisturbed by differential movement of individual granular particles.

The novel features that I consider characteristic of my invention are set forth with particularity in the appended claims. The invention itself, however, both as to its organization and its methods of operation, together with additional objects and advantages thereof, will best be understood from the following description when read in connection with the accompanying drawings, in which:

Fig. 1 is a schematic sectional view of a web coating apparatus, and including a multiple slide hopper constructed in accordance with one embodiment of the present invention and adapted to feed two fluid coating compositions to the coating bead;

Fig. 2 is an enlarged sectional view of the upper portion of the hopper shown in Fig. 1 in combination with the web supporting device and the web to be double coated;

Fig. 3 is a view similar to Fig. 1, but showing another embodiment consisting of a double slide hopper adapted to simultaneously feed three fluid coating compositions to the coating bead;

Fig. 4 is a view similar to Fig. 3, but showing another form of slide hopper for simultaneously feeding three fluid coating compositions to the coating bead;

Fig. 5 is an enlarged view of the embodiment shown in Fig. 4, and showing the manner in which the individual layers of the three coating compositions are formed and combined in the slide hopper and how they move through the coating bead for application onto the web surface; and

Fig. 6 is a vertical sectional view of a slide hopper constructed in accordance with still another embodiment of the present invention and adapted to feed four different coating compositions to the coating bead.

Generally speaking, the present invention consists of a coating hopper having one or more slide surfaces so arranged as to carry by gravity flow two or more different

2

fluid coating compositions from two or more distributing or discharge slots into contact with the surface of a moving web of film base, paper, plastic sheeting, etc. at such a position as to produce a smooth and uniform multiple coating thereon. The novel feature of this invention is the relative location of two or more of the distributing or discharge slots so that they meet in a common line or slot at the upper edge of a slide surface or surfaces in such a position that two or more fluid coating compositions issuing therefrom form a stratified layer arrangement which will then proceed by gravity flow down the sloping slide surfaces to the coating bead across and in contact with which a web is continuously moved to pick up a multiple coating from the bead.

15 Referring now to Figs. 1 and 2, there is shown an apparatus constructed in accordance with one embodiment of the present invention which was successfully used to apply two separate coatings to a support in the manufacture of photographic film. Here there is shown a double

20 slide hopper 10 having a cavity 11 into which one fluid coating composition S is continuously pumped at a given rate by a metering or constant discharge pump P'. The coating composition S is then forced from cavity 11 through a narrow distributing or discharge slot 12 in the 25 form of a ribbon and out onto a downwardly inclined slide surface 13 down which it flows by gravity in the form of a layer 14 into a coating bead 15 formed between the surface of the web W to be coated and the lip or end 16 of the slide surface. The web W is backed up at this 30 point by a roll 17 which may serve as a means for continuously moving the web across and in contact with the bead 15 as well as serving as a means for supporting and holding the web smooth while passing across the bead of coating.

35 This bead technique of multiple coating is well known in the art and is disclosed fully in the above-noted Patents 2,761,791 and 2,761,419. It need only be mentioned here that the bead 15 extends completely across the width of the web W being coated and that the surface of the web

40 W in moving across and in contact with the bead picks up the layers of coating therefrom. It can be seen that with this bead coating technique the coating is not in fact deposited directly onto the web surface by the hopper, but that the hopper merely maintains the coating bead 45 and the web is coated therefrom. With the bead technique of coating, the actual thickness of the coating laid down on the web moved thereacross will be determined by the action of the bead and will vary with the speed of movement of the web and the metered flow rates of the coating 50 compositions from their discharge slots and will not necessarily be equal to, or directly dependent upon, the thickness of the ribbon of coating composition fed to the slide surface or the thickness of the layer formed in flowing down the slide surface.

55 The second fluid coating composition S₁ is continuously pumped into a second cavity 19 by a second metering or constant discharge pump, P'. In accordance with the present invention, from this cavity 19 the composition S₁ is forced through a distributing slot 20 opening

60 onto the slide surface 13 and from which slot it issues as a layer 14' engaging the top of layer 14. It is in the arrangement of these two distributing or discharge slots 12 and 20 that the present slide hopper differs from those shown in U.S. Patent 2,761,419. Whereas in the 65 patented hopper each of the discharge slots is separated by a slide surface down which a layer of coating flows by gravity before joining a layer extruded from a lower slot, in the present invention the exit ends of the two distributing or discharge slots 12 and 20 meet at a common line to form a common slot 21 at the top of the slide surface 13. Coating composition S is delivered through discharge slot 12 at a metered rate of flow, while

simultaneously a second coating composition S_1 is delivered through slot 20 at a metered rate of flow, which may be less than, equal to, or greater than the flow rate for composition S . The two compositions flow in a stratified layer system 14 and 14' down slide surface 13 and form a stratified coating bead 15, see Fig. 2. In Fig. 2 an attempt has been made to show in detail the layer thickness relationship which might occur throughout the flow path. The ratio of layer thicknesses on the web W is directly proportional to the metered flow rates delivered from the discharge slots 12 and 20. However, the ratio of layer thicknesses on the slide surface 13 may vary from the metered rates due to physical property differences between the fluid coating compositions which may cause differential layer velocities while flowing by gravity. In leaving the coating bead 15, and on the moving web W, the layers regain the metered rates of thickness. On the web W the absolute thickness of each layer is a function of the metered rate of liquid flow and the linear speed of the web. The distribution or discharge slots 12 and 20 only perform the function of feeding the fluid coating compositions S and S_1 respectively, uniformly from end to end of the slide surface 13, and do not perform a metering function. Therefore, the same slot width can be used for a great range of flow rates with the metering of flow rates being accomplished in the liquid supply system ahead of the distributing slots. The width of common slot 21 formed by the meeting of distribution slots 12 and 20 is substantially equal to the sum of the widths of slots 12 and 20.

As mentioned above, the novel feature of this embodiment of the present invention is the manner in which the two coating compositions are simultaneously delivered to the slide surface 13 by distributing slots 12 and 20. This is particularly useful when the upper layer of liquid is to be very thin. In this situation, when the system of tandem slides disclosed in U.S. Patent 2,761,419 is used, the surface tension, viscosity and setting characteristics of the liquid and the ability of the liquid to wet the slide surface while flowing alone down the upper slide surface may cause the edges to draw in toward the center, making the layer narrower than desired and causing an undesirable thickening in the edge areas. In extreme cases, the liquid may even solidify on the slide surface, causing interference with the smooth sheet-like flow necessary to produce a uniform coating. By use of the apparatus disclosed in Figs. 1 and 2, the coating composition S_1 can be extruded from discharge slot 20 into a thin layer and be deposited directly onto the layer of composition S extruded from slot 12, traveling with it to the coating bead 15 without edge withdrawal and the thickening effect above mentioned. Commercial coatings have been made with this embodiment of slide hopper having an upper layer wet thickness of .28 mil. This is approximately one-half the minimum thickness possible with the same coating compositions using the tandem slide hopper disclosed in U.S. Patent 2,761,419. Experimental coatings using this new slide hopper have been made with an upper layer wet thickness of .14 mil. The hopper may be provided with conduits C through which a hot or cold fluid may be circulated for the purpose of maintaining the temperature of the coating compositions in the hopper cavities such as to promote proper coating thereof.

After the web has been coated, it may be necessary to set and dry the coatings applied thereto. In the manufacture of photographic film or paper, the coatings applied may be of the type which will set by cooling prior to drying in order to limit the amount of relative flow between the layers themselves or between the bottom layer and the support. In such a case the web W after being coated can be passed through a chill box B and then through the drying chamber D. If the coatings applied are of the type which do not require chilling

before drying, the chill box B can be omitted or bypassed. The web may be pulled from the drying chamber D by a feed or guide roll R.

Another embodiment of my invention is shown in Fig. 3. In this embodiment a third distributing or discharge slot 25 has been added to the embodiment shown in Figs. 1 and 2 in order to deliver another layer of fluid coating composition S_2 onto extended slide surface 26 coplanar with slide surface 13' so as to form a three-layer stratified bead 15' and produce a three-layer coating on the moving web W. The coating composition S_2 is continuously fed into a third cavity 27 by a metering pump P'' . Inasmuch as that portion of the hopper above discharge slot 25 for feeding the coating compositions forming the upper two layers is the same as that shown in Figs. 1 and 2, the parts thereof are designated by the same reference characters as the corresponding parts of the Fig. 1 and 2 embodiment except that they are primed. In this embodiment, any grouping of layer thickness is possible. However, as in the first embodiment, the meeting line of the two upper distribution or discharge slots 12' and 20' makes possible the application of an extremely thin top surface layer. By the addition of more distribution slots and slide surfaces, more layers may be simultaneously applied using the same method for the top two layers.

Another application of the novel feature of this invention is used in the embodiment shown in Figs. 4 and 5. In this case a coating composition S_3 is fed from cavity 30 through a discharge slot 31 onto a slide surface 32. At the same time fluid coating compositions S_4 and S_5 are fed from cavities 33 and 34, respectively, through discharge slots 35 and 36 onto slide surface 37. The discharge slots 35 and 36 meet in a common line or slot 35 at the top of slide surface 37 so that the ribbons of liquid S_4 and S_5 issue therefrom in stratified layer relationship. The layer of composition S_3 issuing from slot 31, after flowing down slide surface 32, joins and moves onto the top of the two layers of composition issuing from slots 35 and 36 to form a three-layer stratified flow on slide surface 37, see Fig. 5, proceeding then through the stratified bead at 15" and onto the web W moving across and in contact therewith to pick up a three-layer coating, see Fig. 5. It will be seen that this arrangement of distributing slots allows the middle layer of coating composition S_4 to be extruded through slot 35 directly between the upper and lower layers of coating compositions S_3 and S_5 , respectively, without the necessity for flowing by gravity in contact with a slide surface. Many coating compositions, such as colloidal dispersions containing high concentration of granular solids, such as silver halide, matting materials, etc., are subject to non-uniform layer formation caused by the retarded progress of the larger particles in contact with the slide surface of the hopper. By the use of this embodiment of the invention the center layer, coating composition S_4 , issuing from the discharge slot 35 may be insulated from physical damage which might result from contact with the slide surface 37 by the bottom layer of coating composition S_5 which may be non-granular. At the same time, the upper layer of coating composition S_3 reaching the common meeting line of discharge slots 35 and 36 via discharge slot 31 and slide surface 32, serves to seal the middle layer of coating composition S_4 from contact with the surrounding air, thus preventing damage by air current and air-borne dirt particles during passage to and through the coating bead 15". Fig. 5 shows the layer conformation in this embodiment in enlarged detail.

Another use of the novel feature of this invention is incorporated in the embodiment shown in Fig. 6 which is a modification of the Fig. 4 and 5 embodiment and has the corresponding parts designated by the same reference numerals primed. In this embodiment an additional discharge slot 40 introduces a fourth coating composition S_6 from cavity 41 into the stratified layer system at the

common meeting line or slot at the top of slide surface 37'. In this case, neither the layer of coating composition S_4 issuing from discharge slot 35' or the layer of coating composition S_6 issuing from discharge slot 40 comes into contact with the slide surface 37' or the surrounding air.

Further variations may be made by providing additional discharge slots and slide surfaces above the common meeting line of two or more discharge slots so that two or more layers may overlay the critical layer or layers which must be protected from contact with a slide surface and/or the surrounding air. The number of discrete layers which can be applied by variations of the invention appear to be limited only by the necessary structural rigidity of the hopper for maintaining uniform distributing slot conformation, the number of available supply sources for the coating compositions used, and the capacity of the equipment necessary for processing the multiple coating to the final dry state.

While I have shown and described certain specific embodiments of my invention, I am aware that many modifications thereof are possible. My invention, therefore, is not to be limited to the precise details shown and described but is intended to cover all modifications coming within the scope of the appended claims.

Having thus described my invention, what I claim as new and desire to secure by Letters Patent of the United States is:

1. In an apparatus for simultaneously applying a plurality of fluid coating compositions to the surface of a web in superposed and distinct layer relationship the combination with a web guiding surface over which the web to be coated is adapted to be continuously moved and held in a smooth condition; of a multiple layer slide hopper comprising an exposed slide surface inclined downwardly toward the web guiding surface and terminating in a lip spaced from the guide surface by an amount slightly greater than the thickness of the web to be coated; wall means forming a discharge slot extending from the interior of said hopper at an acute angle to said slide surface and having an exit end opening onto said slide surface at a point spaced above said lip to provide an uninterrupted and exposed slide portion below said exit end down which a layer of a fluid coating composition extruded therefrom flows by gravity to form a smooth layer of uniform thickness; second wall means forming a second discharge slot extending from the interior of said hopper and having an exit end opening onto said slide surface above the exit end of said first discharge slot and merging therewith into a common slot in said slide surface whereby a layer of fluid coating composition extruded from said second slot flows onto the upper surface of the layer extruded through said first slot and the two layers flow down said uninterrupted slide portion by gravity flow in stratified relation with the layer of coating composition issuing from the first slot supporting the layer of coating composition issuing from the second slot and maintaining the latter layer out of physical contact with said slide portion, and the layer of coating composition issuing from the second slot acting to seal said other layer from contact with the surrounding atmosphere as they issue onto and slide down said exposed slide portion, and means for continuously feeding a fluid coating composition into each of said discharge slots at a predetermined rate commensurate with the thickness desired for each of said layers after coating.

2. An apparatus according to claim 1 characterized by the fact that the exit ends of each of said discharge slots extend transversely of said exposed slide portion in parallel side-by-side relation and merge at the upper end of said slide portion into a common slot whose width is equal substantially to the sum of the individual widths of said two slots, the upper edge of the exit end of said first discharge slot and the lower edge of the exit end of said second discharge slot being joined by a substantially sharp edge forming a common part of said two wall means.

3. In an apparatus for simultaneously applying a plurality of fluid coating compositions to the surface of a web in superposed and distinct layer relationship, the combination with a web guiding surface over which the web to be coated is adapted to be continuously moved and held in a smooth condition; of a multiple layer slide hopper comprising an exposed slide surface inclined downwardly toward the web guiding surface and terminating in a lip spaced from the guide surface by an amount slightly greater than the thickness of the web to be coated; wall means defining a plurality of discharge slots, extending from the interior of said hopper and each having an exit end opening onto said slide surface through which the separate coating compositions are adapted to be extruded in the form of layers, said discharge slots being so arranged that said exit ends thereof merge into a common slot in said slide surface spaced above said lip to provide an uninterrupted exposed slide portion below said common slot down which layers extruded from said discharge slots flow by gravity in stratified relation, said common slot having a width equal substantially to the sum of the widths of said discharge slots whereby the individual layers of coating composition issuing from said individual discharge slots merge in and issue from, said common slot in stratified relation; and means for continuously feeding a fluid composition into each of said discharge slots at a predetermined rate commensurate with the thickness desired for each of said layers after coating.

4. An apparatus according to claim 3 and including further wall means defining another discharge slot extending from the interior of the hopper and having an exit end opening onto said slide surface through which another fluid coating composition is adapted to be extruded in the form of a layer; the exit end of said last-mentioned discharge slot being disposed above said common slot to provide a second uninterrupted exposed slide portion below the exit end of said last-mentioned discharge slot down which the layer extruded from said slot flows by gravity to form a smooth layer of uniform thickness prior to the time it reaches said common slot and flows onto the top of and along with the stratified layers of coating composition extruded from said common slot; and means for continuously feeding a fluid composition into said last-mentioned discharge slot at a predetermined rate commensurate with the thickness desired for the layer issuing therefrom after coating.
